UNITED STATES PATENT OFFICE.

CHARLES E. GODLEY, OF DETROIT, MICHIGAN, ASSIGNOR, BY MESNE ASSIGNMENTS, TO
C. M. HALL LAMP COMPANY, A CORPORATION OF MICHIGAN.

COMPARTMENTAL LAMP.

Application filed February 24, 1928. Serial No. 90,819.

- My invention relates to compartmental lamps, its general object being those of providing simple, inexpensive and easily assembled means for partitioning the lamp casing, 5 for supporting the lamp bulbs in operative relation to the several compartments into which the casing is partitioned off, and for affording controlled circuit connections to the several lamp bulbs.
- 10 More particularly, my invention provides a simple partitioning member which will effectively divide a lamp casing into three compartments, which will support two of the needed lamp bulbs in their operative positions, and which will also retain a lens or window pane in its normal position.
- 15 My invention also relates to a compartmental lamp having a single plug holder mounted on its casing, and provides an arrangement whereby the controlled circuit connections to a plurality of lamp bulbs can be made by a unitary circuit connecting device mounted in the same holder, regardless of the directions in which the several 20 lamp bulbs extend. Moreover, my invention provides a lamp assembly in which a bulb holder functions also for retaining such a circuit connecting device in the plug holder.
- 25 Still further and also more detailed objects will appear from the following specification and from the accompanying drawings, in which
- 30 Fig. 1 is a front elevation of a three-compartment vehicle tail lamp embodying my invention.
- 35 Fig. 2 is an enlarged side elevation of the same.
- 40 Fig. 3 is a fragmentary and enlarged horizontal section taken along the line 3—3 of Fig. 1.
- 45 Fig. 4 is a similary enlarged front elevation of the same lamp with the door or cover member detached.
- 50 Fig. 5 is a vertical section through the same lamp, taken along the line 5—5 of Fig. 1.
- 55 Fig. 6 is a perspective view of the partitioning member.
- Fig. 7 is a rear elevation of the lamp casing, drawn on a reduced scale.
- Fig. 8 is an enlarged longitudinal section through an end portion of one conducting member of the circuit connector.
- The illustrated embodiment shows a horizontally elongated casing 1 provided at its
- mouth with a tubular portion 2 upon which the inner member 3 of the lamp door is sleeved. This door carries a beehive tail light lens 4 disposed below the center of the door, and a pair of relatively higher signal lenses 5 and 6 disposed at opposite sides of the lens 4 and having more elevated axes. The bottom of the casing has the part behind the portion 4 formed into portions of cylinders concentric with the three lenses—namely the portions 5, 6 and 7 of Fig. 7—and the middle portion 6 has a window aperture through which light from a central lamp bulb can reach the license plate which is usually positioned below such a tail lamp. Extending across this aperture is a curved glass pane 8 which preferably has a downwardly projecting portion 8^a extending through the said aperture and corresponding in size to the latter so as to prevent the pane from shifting in position.
- To divide the casing into three compartments respectively behind the three lenses, I provide a partitioning member which can be formed from a single piece of sheet metal 80 as shown in Fig. 6. This member is generally U-shaped in horizontal section and includes a flat back 8 adapted to bear flatwise against the back 1^a of the casing, and a pair of shanks or wings 9 and 10 extending forwardly from the ends of the back portion 8, each of these wings being shaped so as to reach to the top and bottom walls of the casing and to the door. Each wing 9 and 10 has at its forward edge a pair of ears 11 provided with threaded perforations 12 for receiving screws 13 which extend through the door and detachably secure the latter to the partitioning member. Each wing 9 and 10 also has adjacent to its lower edge a finger 14 which projects downwardly at an incline towards the other member and engages the top of the window pane 8, and each finger is threaded to receive a screw 15 which extends through the bottom casing portion 6 and clamps the pane to the casing.
- Each of the wings 9 and 10 is provided with integral bulb-holder formations for engaging the base (15, 17) of one of the two lamp bulbs which have their filaments respectively disposed behind the signal lenses 5 and 6. Each set of these bulb-holder formations preferably includes a pair of wings 18 projecting into the space between the two webs and provided with bayonet slots hav-

ing their entrance openings on the outer face of the wing from which these webs are formed, and a pair of outwardly directed webs 19 for preventing a rocking of the 5 lamp bulb, all after the manner more fully disclosed in my copending application No. 83,749 on lamp-bulb holders, filed January 25, 1926.

To support the medially disposed third 10 lamp bulb 20, I provide a separately constructed bulb-holder having similar anchoring slots 21 and tilt-preventing webs 22 as shown in Fig. 5, and having two legs 23 fastened to the casing back 1^A by screws 24 15 which extend through the partition back 8 and clamp this partition back between the casing back and the feet of the said legs. To eliminate a fastening screw for the third leg 25 of this same bulb-holder, I form the 20 last named leg so that its foot 26 engages the rear edge of the glass pane 8 and provide the bottom of the partition back with a forwardly offset finger 27 (Fig. 5) which bears against the foot 26 and clamps the latter 25 against the edge of the window pane.

Every one of the lamp bulbs is desirably of the usual Ediswan type with one end of its filament grounded through the usual metal collar on the base of the lamp bulb 30 and through the corresponding metallic holder to the metal lamp casing which is grounded according to the usual practice to the common terminal of the three lamp circuits. Then I provide the circuit connections to the axial base terminals of the three lamp bulbs by conductors forming part of a unitary circuit-connecting device which has its insulating body socketed in a tubular plug holder 29. This plug holder extends 35 through aligned perforations in the backs of the casing and the partitioning member and is fastened to one of these, and has the usual rearwardly opening bayonet slots 30 for interlocking with anchoring pins on a terminal plug to which the wires from three 40 separately controlled circuits are connected.

The circuit-connecting device is preferably of the general type disclosed in my copending application No. 92,343, filed 50 March 4, 1926, and includes an insulating body 31 which is partly socketed in the tubular plug holder 29 and which has a longitudinal groove 32 entered by an indentation 33 of the holder (Fig. 5) for preventing 55 rotation of the insulator. Extending longitudinally through this holder and fastened to it by pins 34 (Fig. 3) are a pair of conductors 35 and 36, each of which is bent so as to dispose its forward end axially of one 60 of the lateral lamp bulbs 16 and 17. Each of these conductors has its forward end formed into a cylinder housing the enlarged inner end of a plunger 37 which is continuously pressed endwardly of the conductor by a spring 38 (as shown in Fig. 8) so as

to be pressed against the axial terminal 28 of the adjacent lamp bulb.

The other end of each conductor is similarly formed and provided with a rearwardly spring-pressed plunger 39 for engaging 70 one terminal 40 of an ordinary three-wire plug 41 interlocked with the plug holder 29. A third and shorter conductor 42 carries a spring-pressed plunger 43 for engaging the 75 third terminal of the plug and has a resilient arm 44 fastened to its forward end for engaging the axial terminal of the lower and medial lamp bulb 20. To retain the insulator of this circuit connector in the tubular plug holder 29, I provide the separately 80 formed bulb-holder with an arm 45 engaging the front end of this insulator as shown in Figs. 4 and 5.

With the lamp thus constructed, the bulb-holder 29 can first be secured to the back of 85 the partitioning member. After the latter is slid into the casing, the insulator of the circuit connecting device is slid into the plug holder, the glass pane 8 is slipped into place, and the three-legged lower bulb-holder is 90 then fastened to the casing by means of the screws 24, thereby firmly securing the partitions together with all three of the bulb-holders and the circuit connecting device in 95 their operative positions. Then the attaching of the lower screws 15 to the feet 14 of the partition wings clamps the glass pane firmly to the bottom of the casing.

By varying the lengths and the curvature 100 of the bends in the conducting members 35 and 36 I can readily adapt these to varying spacings of the partition wings and even to different angles between the axes of the plug holder and of the lateral lamp bulbs, so that 105 my construction can be employed in lamps of widely varying sizes and arrangements. Since the assembling is exceedingly simple and since the associated parts automatically align in operative positions, I can also employ cheap labor for the assembling. 110

However, I do not wish to be limited to the details of construction and arrangement above disclosed, or to the particular shape and arrangement of the illustrated lamp, as 115 many changes might obviously be made without departing either from the spirit of my invention or from the appended claims.

I claim as my invention:

1. In a compartmental lamp, a forwardly 120 open casing, a partitioning member of substantially U-shaped cross-section disposed within the casing and having its middle portion secured to the back of the casing, the said portion being shorter than the casing and the said member having its legs extending forwardly to the mouth of the casing, each of the said legs having a bulb holder integral therewith, a third bulb holder mounted on the said back, and an attaching-plug holder fast on the middle por- 125 13

- tion and extending through the back of the casing.
2. In a compartmental lamp, a forwardly open casing, a partitioning member of substantially U-shaped cross-section having its middle portion adjacent to the back of the casing and having its legs extending forwardly and reaching to opposite lateral walls of the casing, each leg having a perforation and a bulb-holder at the perforation, a third bulb-holder having a base bearing against the back of the partitioning member, and means for simultaneously securing the third bulb-holder and the said portion of the partitioning member to the back of the casing.
3. In a compartmental lamp, a forwardly open casing, a pair of spaced partitions each provided with a perforation and with a bulb-holder at the perforation, two lamp bulbs respectively mounted in the said holders and having opposed base ends both extending into the space between the partitions, a third bulb-holder mounted in the said space, a lamp bulb mounted in the third bulb-holder, and a unitary circuit connector having three circuit terminal members extending through the back of the casing and each including a resilient portion disposed in the said space and engaging a base of one lamp bulb.
4. In a lamp, a forwardly open casing having an aperture in its bottom, a glass pane held against the said bottom as a closure for the aperture, and a bulb-holder disposed above the glass pane; the bulb-holder having at one side of its axis a pair of feet secured to the back of the casing and having at the opposite side of the said axis another foot engaging an edge of the pane to prevent the holder from rocking about its first named foot.
5. In a compartmental lamp, a forwardly open casing, a partitioning member including a back portion secured to the back of the casing and a pair of partitions extending forwardly respectively from the ends of the said back portion, the casing having an aperture in its bottom, and a glass pane disposed within the casing and closing the aperture, each partition having an integral finger engaging the glass pane to press the latter against the bottom of the casing.
6. A compartmental lamp as per claim 5, including screws respectively connecting the bottom of the casing with the said fingers for clamping the fingers against the pane.
7. In a lamp, a compartmental casing having a tubular holder projecting from its back and opening into one compartment of the casing and provided behind the said back with means for engaging a wire terminal plug, lamp bulbs having their bulbs respectively in the several compartments of the casing and having their base ends projecting into the compartment into which the tubular holder opens a circuit connector for connecting the terminals of the wire terminal respectively with the said lamp base ends, and bulb-holders for respectively supporting the lamp bulbs, the circuit connector being slidably inserted in the tubular holder rearwardly from the interior of the casing, and means carried by the casing for limiting the said rearward insertion, one of the bulb-holders having a portion engaging the circuit connector to hold the latter in operative position.
8. In a compartmental lamp, a forwardly open casing having a perforation in its back; a partitioning member including a back portion and a partition extending forwardly from the back portion and provided with a bulb-holding formation; a lamp bulb mounted in the bulb-holding formation, a tubular holder secured to the said back portion and extending rearwardly therefrom through the said perforation in the partition, an insulator mounted in the tubular holder; and circuit-connecting means including a conducting member mounted in the insulator and a pair of spring-pressed plungers mounted respectively in the ends of the conducting member, one of the said plungers having its free end extending rearwardly within the said tubular holder, the conducting member extending inwardly of the casing beyond the said holder and being bent to dispose its other end adjacent to and in axial alinement with the bulb-holding formation, the other of the said plungers being mounted in the said other end and directly engaging the base end of the lamp bulb.
9. In a lamp, a casing having a wall thereof provided with an aperture, a tubular holder extending through the aperture, a lamp-bulb holder supported within the casing and spaced from the holder, and an insulator slidably inserted in the holder from the inner end of the latter, the insulator having a stop formation to limit the extent of the said slidable insertion, the lamp-bulb holder having a portion engaging the insulator to retain the latter in the holder.
10. A compartmental lamp as per claim 3, in which the circuit connector is inserted rearwardly through the back of the casing, there being means on the casing engaging a portion of the circuit connector to limit the extent of such rearward insertion, the said third bulb-holder having a portion thereof engaging the circuit connector to prevent forward movement of the circuit-connector.
11. In a lamp, a forwardly open casing having an aperture in its bottom, a glass pane extending through the aperture and having an enlarged upper portion seated upon the upper face of the said bottom, and a bulb-holder having a pair of feet secured at one side of its axis to the back of the casing and having at the other side of the said axis an

other foot clamped between the said back and an edge of the said enlarged portion of the glass pane.

12. In a lamp, a forwardly open casing, a tubular holder extending through the back of the casing, a plurality of lamp bulbs supported within the casing with their axes transverse of and radiating from the axis of the said holder, and a unitary circuit connector; the said connector comprising an insulator mounted in the said holder, con-

ducting members each having a portion extending through the insulator parallel to the axis of the tubular holder and another portion disposed in axial alinement with one of the lamp bulbs, and spring-pressed plungers respectively mounted in the last named portions of the conducting members and each engaging the base of one of the lamp bulbs.

Signed at Detroit, Michigan, February 20
12th, 1926.

CHARLES E. GODLEY.
